* cited by examiner

Primary Examiner — Ian Simmons*Assistant Examiner* — Rashida C McCoy(74) Attorney, Agent, or Firm — Lewis Roca Rothgerber LLP(57) CLAIM

The ornamental design for a shoe cover, as shown and described.

DESCRIPTION

FIG. 1 is a perspective view of a shoe cover showing my new design;

FIG. 2 is a front view thereof;

FIG. 3 is a back view thereof;

FIG. 4 is a left view thereof;

FIG. 5 is a right view thereof;

FIG. 6 is a top view thereof; and,

FIG. 7 is a bottom view thereof.

The broken line showing of the shoe is for the purpose of illustrating the environment and boundary related to the claimed design and forms no part of the claimed design.
